UNITED STATES PATENT OFFICE.

LEO HIRSCHFELD, OF NEW YORK, N. Y.

POCKET-PARTITION FOR BOXES.

SPECIFICATION forming part of Letters Patent No. 683,761, dated October 1, 1901.

Application filed June 7, 1901. Serial No. 63,546. (No model.)

To all whom it may concern:

Be it known that I, LEO HIRSCHFELD, a citizen of the United States, and a resident of the city of New York, borough of Manhattan, in 5 the county and State of New York, have invented a new and Improved Pocket-Partition for Boxes, of which the following is a full, clear, and exact description.

The purpose of the invention is to provide 10 a pocket-partition for boxes intended to contain chocolate drops or similar confectionery, and to construct the partition in a number of sections having guides upon which they slide, each section being independent of the other 15 and having independent movement, so that the sections may be so arranged that when in given positions with respect to each other the sections will form a series of pockets, each adapted to contain a piece of confectionery, 20 whereby each individual piece is separately contained in a pocket and one piece is prevented from having engagement with another.

The invention consists in the novel construction and combination of the several parts, as will be hereinafter fully set forth, and pointed out in the claims.

Reference is to be had to the accompanying drawings, forming a part of this specification, 30 in which similar characters of reference indicate corresponding parts in all the figures.

Figure 1 is a plan view of a box in which an upper tray is exposed having the improved partition applied. Fig. 2 is a longitudinal 35 vertical section through the box, taken practically on the line 2 2 of Fig. 1. Fig. 3 is a transverse section through the box and trays, taken substantially on the line 3 3 of Fig. 2; and Fig. 4 is a detail perspective view of a 40 portion of a partition removed from the box or tray.

A represents a box, and B trays, which are supported in the box either one upon the other or in any other suitable manner.

45 C represents the partition. The partition for each tray is of the same construction and consists of a series of angular base-sections, each base-section comprising an upwardly-extending member 10 and a horizontal bottom section 11 and a series of guides 13, which pass through openings 12 in the upwardly-extending members 10 of the base-

sections of a partition, as is best shown in Figs. 3 and 4. The base-sections of the said partition may be made of pasteboard, card- 55 board, or thin paper, single or double, or other suitable material. In the drawings the sections are shown as made of paper of light weight doubled upon itself. The guides 13 are preferably of a stouter or stiffer material, 60 and said guides are adapted to extend from end to end of the box or tray in which the partition is to be placed, while the base-sections of the partition are transversely located in the box or tray. 65

In operation the base-sections are placed one upon the other and the guides 13 are passed through the openings 12 in the vertical members of the base-sections; but one end section (designated as c and shown particularly in 70 Fig. 2) is placed upon the guides 13 in a position the reverse of the other sections, so that the vertical member 10 of this particular end section c may be carried to an engagement with the inner face of an end of the box 75 or tray. The other sections, which may be collectively located at the center of the box or tray, are then slid one from off the other until their horizontal members 11 slightly overlap, as shown in Fig. 2, thus forming a 80 series of pockets 14, each pocket complete in itself and adapted to hold an article—as, for example, a chocolate drop or other piece of candy—so that the various pieces in the tray or box will not rub one against the other, and 85 the design or ornamentation on each piece may be accurately preserved in transportation, even when the package is roughly handled.

Having thus described my invention, I 90 claim as new and desire to secure by Letters Patent—

1. A pocket-partition for boxes, comprising a plurality of flat bars extending in the same general direction and placed on edge 95 for the purpose of acting as partitions, and a plurality of movable members extending in a general direction at right angles to the direction of said flat bars, said movable members being provided with overlapping base-sections and with vertical sections acting as partitions and also provided with longitudinal slots for engaging said flat bars. 100

2. A pocket-partition for boxes, comprising

ing a frame provided with a bottom, flattened guide-bars disposed edgewise toward said bottom and spaced asunder therefrom for the purpose of serving as partitions, and a plurality of base-sections provided with upwardly-extending members, said members being provided with vertically-disposed longitudinal slots for engaging said flattened guide-bars.

In testimony whereof I have signed my name to this specification in the presence of 10 two subscribing witnesses.

LEO HIRSCHFELD.
